(57) **CLAIM**

The ornamental design of a shower plate as shown and described.

DESCRIPTION

FIG. 1 is a perspective view of the shower plate, showing our new design;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a right side view thereof;

FIG. 8 is a left side view thereof;

FIG. 9 is a cross-section view taken from FIG. 3;

FIG. 10 is a second cross-section view taken from FIG. 3; and,

FIG. 11 is a detail view taken from FIG. 2.

The broken lines are for the purpose of illustrating portions of the article and form no part of the claimed design.
